UNITED STATES PATENT OFFICE.

JOHN WILLIAM WEISER, OF CHICAGO, ILLINOIS.

CLAMP FOR CABINET-MAKERS.

SPECIFICATION forming part of Letters Patent No. 292,891, dated January 22, 1884.

Application filed October 4, 1883. (No model.)

To all whom it may concern:

Be it known that I, JOHN W. WEISER, of Chicago, in the county of Cook and State of Illinois, have invented certain new and useful Improvements in Clamps for Cabinet-Makers; and I do hereby declare that the following is a full, clear, and exact description of the invention, reference being had to the accompanying drawings, and to the letters of reference marked thereon, which form a part of this specification.

This invention relates to clamping devices, such as are used by joiners and cabinet-makers in bringing joints of separate parts properly together in gluing or otherwise fastening them.

The principal object of the invention is to provide an improved construction in such clamps, whereby they are adapted to be more quickly applied to and disengaged from the work.

To this and other ends that will further appear the invention consists in the matters hereinafter set forth and claimed.

25 In the accompanying drawings, Figure 1 is a perspective view of a clamp of the character referred to constructed in accordance with my invention. Fig. 2 is a longitudinal central vertical section thereof.

30 A is the longitudinal bar of the clamp. B is a fixed bracket at one end thereof, and C is a movable bracket, adapted to slide upon and engage the bar A at any desired point of its length. D is a lever operating a cam or eccentric, D', pivoted to the bracket B, and arranged to bear inwardly against the work by a downward movement of the lever D. B' is a movable block, suspended from the beam A by the link B' in bearing against the face 35 of cam D', and therefore interposed between the face of the said cam and the adjacent surface of the work or article upon which the clamp bears in use.

To describe the illustrated construction of 45 the device more particularly, the bracket B is duplex in form, or provided with a slot, b, as clearly indicated in Fig. 1, and is attached to or forms part of a metal plate, b', let into the under face of the beam, and secured thereto 50 firmly by the vertical bolts b² b³.

Within the slot b of the duplex bracket B is inserted the flat head D² of the lever D, and said head is pivotally held in place by the stout pivot-pin d, which forms the axis or center of motion of said lever. The head of the 55 lever has an eccentric portion or cam, D', formed thereon, and constructed to throw inwardly or toward the opposite end of the beam A by a downward movement of the lever D, as shown. On the outer edge of the lever-head, or opposite the cam-face D', said head is made concentric for a suitable distance, and is provided with the teeth or notches d' on the concentric edge.

Above the lever-head, and within the slot 65 b of the bracket, is a pawl, E, pivoted to rise and fall freely on the pin e. The outer or lower end of this pawl is constructed to engage the teeth d' on the lever-head. The opposite end of said pawl is flexibly connected 70 with a rod, F, which rises through the plate b, and through an aperture in the beam A, and reaches to a point slightly above the upper surface of the beam when the pawl is in engagement with the notches of the lever-head. 75 The upper portion of the aperture in the beam, through which the said post rises, is enlarged to form a recess, f', within which is placed the expanding coiled spring F', surrounding the post F, and held in place thereon by the button f, screwed or otherwise secured upon the top of the post. The spring F' being expansive, by its upward pressure upon the button f, lifts the inner end of the pawl E, and throws the opposite end or point of said pawl into 85 engagement with the ratchet d' of the lever-head. When it is desired to lift the lever D, therefore, it is obviously necessary to depress the button f, so as to lift the pawl out of engagement with said ratchet.

In or upon the upper surface of the beam A, for a greater or less portion of its length as may be desired for the class of work for which the clamp is to be used, is secured a metallic rack, A', having its teeth a preferably cast, 95 filed, or otherwise formed at, say, an eighth of an inch or other short interval apart. The movable bracket or block C is made of the same thickness as the beam A, and is of considerable length, so as to bear broadly against 100

the lower surface of the said beam. The movable bracket C is suspended from the beam by means of the pawl-block C² and links C'—one on each side of the bracket and beam. The 5 pawl-plate C² is constructed with teeth c on its under surface, adapted to engage with the teeth a of the rack A'. The links C' are of such length as to allow the plate C² to be lifted out of engagement with the rack-teeth when 10 the clamp is disengaged from the work, in order that the bracket C may be slid along the under surface of the beam to any desired point thereon, after which the block is let fall, so as to bring its teeth into engagement 15 with the rack in an obvious manner.

As previously set forth, the teeth a of the rack A' are relatively small and close together, so as to permit the movable bracket and pawl-plate C² to be shifted laterally through short 20 intervals, and to permit an accurate adjustment of said bracket to the object to which the clamp is applied, and whereby less movement of the lever D and cam D' is required than would otherwise be necessary. In order 25 to provide the necessary strength in the connection between the bracket and beam in the use of such small teeth, the pawl-plate C² is made of considerable length, and is provided with a number of teeth c upon its under surface, so as to hold said pawl-plate securely 30 from longitudinal movement upon the beam under any strain that may come upon the bracket.

The movable block B' is suspended loosely 35 from the beam A by making the link B², by which it hangs, larger than the beam. By this means said block may not only be moved freely lengthwise of the beam, but it may also tilt out of a vertical position, or laterally out 40 of parallel with the face of the bracket C, so that the clamp may be made to bear squarely upon other than parallel surfaces. The entire block B' may be either of metal or of wood. When of the latter, the link B² may be a cast 45 extension of a back plate, B³, screwed or otherwise fastened to the block B', and forming a durable bearing-surface, against which the eccentric or cam face D' of the lever-head bears.

50 The operation of the clamp is as follows: To lift the lever D, the button f is depressed by pressure of the thumb of one hand, while the other is applied to raise the lever. The lever being lifted to its utmost height, and the cam D' being thereby retreated, the block B is pushed or allowed to fall against said cam. The bracket C is then set at the desired point upon the beam, after which the clamp is applied to the article or parts to be compressed, 55 when, by a downward movement of the lever D, the movable block B is forced inward, and the work of compression thereby effected. The pawl E, actuated by the spring F', takes into the ratchet d', and holds the cam D' in 60 whatever position it is given in depressing the

lever D. The movable block B', in the operation of compression, adjusts itself readily to the direction of the face against which it bears, and all motion of the moving parts is limited to the external surface of the plate B³, in contact with which the face of the cam works. 70

It is obvious that the power derived from the cam properly constructed for the purpose is greatly superior to that obtained in the use of clamp-screws heretofore commonly employed in clamps of this character, and it is also obvious that in combination with a cam and lever for working the same a notched plate, A, having small notches, by which the clamp is adapted to be set close to the work in 80 the first instance, is desirable. To permit the notches or teeth a to be made small enough for this purpose, they must obviously be of metal, requiring the use of a metal plate, A'. Said plate, instead of being narrower than the 85 face of the beam, to which it is applied, as shown, may be of the full width of said beam, if preferred.

I claim as my invention—

1. The combination, with the beam of a 90 clamp, of a stationary bracket secured to one end thereof, an opposing movable bracket upon the beam, a block connected loosely with the beam so as to have free vertical and lateral movement, and a cam pivotally mounted in the 95 stationary bracket and constructed to bear upon the said movable block, substantially as described.

2. The combination, with the clamp-beam A, provided with a stationary bracket at one 100 end and a metal plate having a series of notches, a, of a movable bracket, C, opposed to the stationary bracket, a movable pawl-plate, C², provided with teeth adapted to engage with the said notches, and links pivotally connected 105 at their ends with the said bracket and pawl-plate, substantially as described.

3. The combination, with the beam A of a clamp provided with a stationary bracket at one end, of a notched metal plate, A', secured 110 to the beam, a movable bracket, C, opposed to the stationary bracket, a pawl-block, C², constructed to engage the notched plate, said pawl-block and bracket being arranged upon opposite sides of the beam, and links C', connected with the pawl-block and bracket, substantially as described. 115

4. The combination, with the beam of a clamp, a stationary bracket secured to one end thereof, and an opposing movable bracket, of 120 a cam mounted in said stationary bracket provided with a suitable ratchet and lever, a pawl constructed to engage the ratchet, and means for releasing the pawl constructed to operate from the top of the beam, substantially 125 as described.

5. The combination, with the beam A of a clamp provided with a stationary slotted bracket, B, at one end, and an opposing movable bracket, of the lever D, having a head, 130

D², pivotally connected with the stationary bracket and constructed with an eccentric portion, D', and a notched concentric portion, d', a self-acting pawl, E, constructed to engage the notches d', and means for releasing the pawl from engagement with the notches, substantially as described.

In testimony that I claim the foregoing as my invention I affix my signature in presence of two witnesses.

JOHN WM. WEISER.
